ICE CUBE SHAVER

Alfred A. Melcher, Huntington Park, and Frederick H. Porter, Beverly Hills, Calif., assignors, by direct and mesne assignments, to Francis Hann

Application April 6, 1935, Serial No. 14,990

4 Claims. (Cl. 83—62)

This invention has to do generally with ice crushing or shaving devices, and has been developed particularly with the view of providing a conveniently simple and efficient device for shaving the usual small-size ice cubes for beverages, or a variety of household purposes.

In its preferred form, the present device comprises a body having a vertically extending passage of rectangular cross section which receives the ice cubes, a rotating ice shaving element in the lower portion of the passage, and a base so designed as to conveniently rest upon or fit over the top of a container, such as a cocktail shaker, glass, or the like, into which the ice shavings are discharged. The principal advantages of the invention reside in the features which render it so especially desirable for this particular use, that is, shaving small-size ice cubes, and in the facility with which the device may be employed in shaving the ice directly into small containers in which the ice is to be immediately used.

All the various objects and aspects of the invention will be made most readily apparent and explained to best advantage by proceeding directly with a description of the invention in one of its typical and preferred forms. Throughout the description, reference is made to the accompanying drawings, in which:

Fig. 1 is a front elevation of the device illustrating the slotted body feature;

Fig. 2 is a plan view of Fig. 1;

Fig. 3 is a fragmentary vertical sectional view illustrating the ice shaving element partially in section, and showing the base of the apparatus resting on the top edge of the container;

Fig. 4 is a perspective showing certain parts of the ice shaving element and shaft assembly; and

Fig. 5 is a side view showing one of the cutter segments removed from the shaft.

The upper portion 10a of the body 10 of the device is made specially to receive ice cubes and to provide a guide passage through which the cubes are fed to the rotating shaft element, hereinafter described. As best illustrated in Fig. 2, the upper portion 10a of the body is rectangular or square in cross section, and forms a vertical passage 11 extending continuously through the lower and somewhat enlarged portion 10b of the body and the base flange 12. Section 10b may also be conveniently made rectangular in cross section. The cross sectional dimensions of passage 11 preferably will be just slightly larger than the corresponding dimensions of an ice cube.

As best shown in Fig. 3, a lip 13 depends from the periphery of the base flange 12, and within

the cavity formed by the lip portion is placed a ring or gasket 14 of suitable comparatively soft material, such as cork. The purpose of gasket 14 is to prevent injury to the top of a glass or container 15 upon which the device rests and into which the ice shavings fall.

A somewhat elongated open and vertical slot 16 is formed in one of the walls of upper body section 10a, the purpose of this slot being to enable one to press the ice cubes in passage 11 down against the shaving element by inserting the thumb through the slot. The latter however is terminated sufficiently far above the cutter as to eliminate any danger of injury to the finger through contact therewith. The shaving element, generally indicated at 17, is carried on a shaft 18 which comprises a portion 18a of octagonal cross section extending between the walls of body portion 10b, and an integral downwardly curved arm 18b terminating in a handle 18c. The section 18d between portions 18a and 18b of the shaft and handle arm assembly is journaled in bearing 19 formed integrally to the wall of the body. As illustrated, end play in the shaft toward the left is limited by the engagement of the handle arm shoulder 20 with the end face of bearing 19.

Broadly speaking, the shaving element 18 may be of any suitable construction, although the illustrated type is preferred because of its effectiveness in disintegrating the ice in the form of shavings, as distinguished from crushed particles, and because of the smoothness with which the element acts on the ice. As best seen from Figs. 4 and 5, the shaving element comprises a plurality of cutter sections or laminations 21 having central openings 22 of octagonal or other suitable shape, and which receives the correspondingly shaped shaft 18a. The body portion 21a of each lamination 21 is circular in shape, and carries a plurality of peripheral teeth 23, the outer surfaces 24 of which project tangentially from the peripheral surface of the body. As best illustrated in Fig. 5, the forward faces 25 of the teeth, instead of lying in radial planes, as illustrated in one instance by the radius R, extend substantially parallel therewith but are offset a short distance D. By thus offsetting the forward faces of the teeth, the latter, upon coming into engagement with the ice, are given to some extent a breaking or chipping action as well as a cutting or shaving action.

It has been found that where the cutter teeth are made the same width as the body 21a of the lamination, there is a tendency for ice to ac-

cumulate between the teeth to such an extent that the cutter becomes rapidly packed with ice out to the surface of the teeth, thereby rendering the cutter substantially ineffective until the 5 ice is removed. In order to prevent the cutter from thus becoming packed with ice, the teeth 15 23 are made somewhat narrower than the bodies 21a of the laminations, so that instead of tending to accumulate and pack between the teeth, 10 the ice shavings are removed or stripped from the cutter as fast as they are deposited.

The laminations are arranged on the shaft in such relative positions that the teeth 24 of adjacent laminations are offset 45°, thereby providing 15 for a smoother cutting action than would be the case where the teeth were arranged in alignment longitudinally of the shaft. While it will be understood that if desired, the cutting assembly 20 may be formed as one single piece or body fitted to the shaft, the limited structure is preferred because of greater facility in manufacture, since the individual laminations may readily be made as castings or by a simple stamping operation.

When assembled on the shaft, the laminations 25 are clamped between shoulder 27 of the shaft and nut 28 threaded on the outer end thereof, the nut also serving to journal the shaft within bearing 29. As illustrated in Fig. 3, the shaving element 17 is positioned within the body so that it 30 projects a short distance up into the lower end of upper body section 10a, thus engaging the ice cube while the latter is firmly confined within passage 11. It will be noted that the toothed disintegrating roll may have an effective length at 35 least as great as the distance between the walls of portion 10a which surmount the more widely spaced walls of the chamber 10b in which the roll is journaled. At the same time, the ends of the roll are spaced from the chamber walls so that clearance is provided for the ice shavings.

40 It is believed that the operation of the device will be readily apparent from the foregoing. One or more ice cubes are fed down through the passage 11 and pressed against the shaving element while the cutter teeth are being rotated in the 45 direction indicated by arrows in Fig. 4. In connection with the operation of the cutter, it may be mentioned that instead of continuing to rotate the cutter in one direction, the most rapid and effective disintegration of the ice cubes may 50 be accomplished by racking or alternately rotating the cutter through short distances in opposite directions. By rotation in a forward direction, the teeth principally have a cutting or shaving action, and by rotation in the opposite direction, they have essentially a chipping or breaking 55 action on the ice. As they are cut from the ice cubes, the shavings drop down into the container 15, ample clearance being provided between the shaving element and the wall of the lower enlarged portion 10b of the body, to pass the shavings without clogging. As illustrated in Fig. 3, the lower end of body section 10a remains open and unobstructed since, preferably, the shaving element extends no higher than the lower end of 60 10a, thereby assuring ample space for the immediate removal of the ice shavings as they are cut from the ice cubes.

The external dimensions of column 10a are such as to enable it to be conveniently grasped in

one hand so that the device may be firmly positioned on the container. When the crank 18b is turned with the right hand, column 10a may be grasped in the left hand and the thumb of the left hand inserted through the slot 16 to press the cubes downwardly.

We claim:

1. An ice cube disintegrating device comprising a hollow body including walls defining a base portion and a top portion, said top portion being vertically elongated, one of the walls of said top portion having a vertically extending slot, a rotatable ice disintegrating element journaled in said base portion, and a hand crank for rotating said ice shaving element, said top portion being of a size to receive a plurality of cubes and also to be conveniently grasped in one hand to hold the device on the container while at the same time the top cube is engaged through said slot by a digit of the same hand to press the cubes 20 downwardly into engagement with said ice disintegrating element.

2. An ice cube disintegrating device comprising a body having walls forming an upper vertically extending hollow ice cube receiving column 25 and a lower downwardly open chamber, a rotatable ice disintegrating element journaled in said chamber, and a hand crank at one side of the device for rotating said element, said body having a bottom portion adapted to rest on the upper edge of a container to support the device on the container and said column being of a size to be conveniently grasped in one hand to hold the device on the container, the wall of said column which faces the operator as the crank is turned 35 by the other hand having a vertical slot therein through which the thumb of the hand which grasps the column may be inserted to press downwardly the ice in the column.

3. An ice cube disintegrating device comprising a body having walls forming an upper vertically extending ice cube receiving column and a lower chamber, a toothed roll rotatable on a horizontal axis and journaled in opposite walls of the chamber, said walls being spaced apart further than the surmounting walls of said column so that the effective length of the roll may be at least as great as the distance between said column walls with the ends of the roll spaced from said chamber walls to provide clearance 50 around the roll ends, and means maintaining the spacing of the roll ends from the chamber walls.

4. An ice cube disintegrating device comprising a body having walls forming an upper vertically extending hollow ice cube receiving column 55 and a lower downwardly open chamber, one of the walls of said top portion having a vertically extending slot, a rotatable ice disintegrating element journaled in said chamber, said body having an annular flanged bottom portion adapted 60 to rest on the upper edge of a container such as a tumbler to support the device on the container, said column being of a size to be conveniently grasped in one hand to hold the device on the container while at the same time ice in said column 65 is engaged through said slot by a digit of the same hand to press the ice downwardly into engagement with said ice disintegrating element.
